CLAIM

The ornamental design for a rack for dispensing link chain, as shown and described.

DESCRIPTION

FIG. 1 is a perspective view of a rack for dispensing link chain showing my new design;

FIG. 2 is a front elevational view thereof;

FIG. 3 is a left side elevational view, the right side being a mirror image thereof;

FIG. 4 is a top plan view thereof;

FIG. 5 is a rear elevational view thereof; and

FIG. 6 is a bottom plan view thereof.

*Fig. 1**Fig. 2**Fig. 3**Fig. 4**Fig. 5**Fig. 6*
